2,442,058

REMOTE CONTROL HYDRAULIC APPARATUS

Herbert E. Page, Dayton, Ohio

Application December 26, 1945, Serial No. 637,278

15 Claims. (Cl. 103—37)

1

My present invention relates to a remote control hydraulic apparatus, and more particularly to an apparatus for delivering hydraulic fluid with a pressure and volume output which will vary in accordance with predetermined load conditions.

An object of the invention is to make an improved and simplified remote control hydraulic apparatus.

Another object is to make a hydraulic apparatus having an initial high capacity output and a secondary lower capacity higher pressure output.

A further object is to make a hydraulic apparatus having adjustable controls for increasing automatically the hydraulic pressure applied upon a predetermined increase in the load.

A still further object is to make a plural actuating hydraulic apparatus adapted for an initial high volume, low pressure delivery under light load, and changing automatically to a predetermined high pressure, low volume delivery upon the imposition of a predetermined load.

In order to attain these objects, and others which will be apparent from a perusal of the following description and the accompanying drawings, I provide in accordance with one feature of the invention an apparatus having a plurality of cylinders of selected sizes, which are disposed at different distances from a fulcrum. Pistons are mounted to operate in the cylinders, through lever arms which may have a common fulcrum, to deliver different volumes of fluid at predetermined pressures in each. By means of simple controls the volume and pressure output of liquid by the device may be varied as required to meet predetermined or encountered load conditions.

These and other features of the invention will be apparent from the following description and the accompanying drawings, in which:

Figs. 1, 2 and 3 are respectively plan, side and end elevations of a hydraulic apparatus embodying the present invention;

Fig. 4 is a longitudinal vertical section taken on the line 4—4 of Fig. 1;

Fig. 5 is a transverse vertical section taken on the offset line 5—5 of Fig. 4;

Fig. 6 is a fragmentary transverse horizontal section taken on the line 6—6 of Fig. 5;

Fig. 7 is a vertical longitudinal sectional view through a block incorporating the principal actuating parts of the apparatus taken on the line 7—7 of Fig. 5;

Fig. 8 is a similar view taken on the line 8—8 of Fig. 5; and

Fig. 9 is a horizontal transverse sectional view

2

through the same block taken on the line 9—9 of Fig. 5.

Referring to the drawings in detail, which illustrate a preferred embodiment of my invention, 5 a casing 10 of sheet metal or other suitable material has a cylinder block 11 mounted within an end thereof. A liquid reservoir or storage cylinder 12 has one end thereof sealed in an annular recess 13 in the block 11. The other end of the reservoir is sealed in a recess 14 in an end plate 15. A bolt 17 having a sealing gasket 18 under the head thereof, passes through the end plate and is screwed into a threaded opening in the block to draw the reservoir cylinder parts together into liquid-tight sealed relation. A second liquid reservoir 19 is mounted above the reservoir 12 and feeds liquid by gravity into the lower reservoir through a passage 20 interconnecting the two reservoirs. A filler pipe 21 extends upwardly from the upper reservoir 19 to a point just below the level of the casing 10, and a filler cap 22 is secured in an opening in the casing over the filler pipe 21.

A pair of bearing supports 24 and 25 project 25 upwardly from the forward or discharge end of the block 11 and in them a fulcrum shaft 26 is mounted for pivotal movement. An end portion 27 of the shaft 26 projects outwardly through an opening in a side of the casing 10. An operating 30 handle lever 28 is keyed to the projecting end portion 27 of the shaft 26, and a piston operating lever 29 is keyed to the shaft 26 between the bearing supports 24 and 25.

A pivot pin 32 is mounted in an opening drilled 35 transversely through the piston operating lever 29 to have a press fit in the opening with both ends of the pin projecting out from the sides of the lever. A pair of piston connecting links 30 and 31 are mounted with their upper ends pivoted 40 one on each of the projecting ends of the pivot pin 32. The lower end of each of the piston connecting links 30 and 31 is divided, as shown in Fig. 5, and is connected pivotally to an upright projection 33 on the upper end of each of a pair 45 of pistons 34 and 35, respectively.

The piston 35 is illustrated as being larger in diameter than the piston 34, it being apparent, however, that the diameters of the pistons may be varied at will, and should be predetermined prior 50 to manufacture so as to produce the pressures desired in the operation of the apparatus.

The pistons 34 and 35 are mounted in cylinders 37 and 38 machined in the block 11. The walls of all the cylinders and pistons are finished in accordance with good current practice, such as

by guiding, lapping, honing, or otherwise to produce a desired degree of smoothness and regularity. Each cylinder has an annular ring groove 39 in which is mounted a sealing ring 40 preferably of resilient synthetic material.

A third piston connecting link 41 is pivoted in a notch 42 in the outer end of the piston operating lever 29, the lower end of the link 41 being connected to a third piston 43. This third piston is generally similar to the other two, but is considerably longer and, as here illustrated, larger in diameter than either of the other two pistons. The piston 43 is mounted in a cylinder 44 machined in the block 11 similarly to the other two cylinders 37 and 38. The piston 43 also is provided with a sealing ring 45 mounted in an annular groove therein.

Fluid passages are provided in the block from the reservoir 12 to the cylinders, the flow of fluid therethrough being controlled by valves and other mechanisms in the following manner:

A main inlet passage 47 opens into a lower portion of the lower reservoir 12 and extends forwardly to the plane of the lower portion of the offset sectional plane of Fig. 5, as indicated by the line 5-5 of Fig. 2. At this plane the passage opens into a laterally drilled passage 48, the exposed end 49 of which is plugged. From this lateral passage 48 two passages 50 and 51 extend upwardly, in rear of the high pressure cylinders 37 and 38 respectively. Since both of these upwardly extending passages are similarly constructed, only the right hand one 50 as shown in Fig. 5 will be described in detail. This passage also is shown sectionally in Figs. 4 and 7.

The upper portion of each of the passages 50 is enlarged as at 52 and is further enlarged as at 53. A seat for a ball check valve is provided at each of these two enlargements of the passages, and ball check valves 54 and 55 are mounted on the seats thus provided. The enlarged upper end 53 of each passage is threaded, as shown in Fig. 7, and a plug 57 is screwed into it to seal the passage. Horizontal passages 58 and 59 connect the first enlarged portions 52 of the passages 50 and 51 into the lower ends of the cylinders 37 and 38, respectively. The forward ends of both of the horizontal passages 58 and 59 are plugged as at 60, see Fig. 7.

A cylindrical cam chamber 61 is drilled transversely of the block 11 with its axis passing through the axes of the vertical passages 50 and 51. A cam 62 is inserted in the cam chamber 61, and has enlarged cylindrical end portions 63 and 64 thereof journaled in the cam chamber outwardly beyond the vertical passages 50 and 51. A sealing ring 65 is mounted in a groove near the outer end of the cam 62, and a snap retaining ring 67 is inserted in an annular groove in the wall of the cam chamber to overlie the outer end of the cam to secure it in position. A cam operating handle 68 is mounted on a projecting stem portion 69 of the cam, and is secured thereto as by a pin 70. A spring pressed ball 71 inserted in a recess 72 of reduced diameter in the base of the cam chamber 61 exerts a resilient outward positioning force on the cam to hold it against the snap retaining ring 67.

A pair of cam lobes 73 and 74 are provided on the cam 62, one lobe being positioned in alignment with each of the passages 50 and 51, respectively. The cam lobes are of a height to provide sufficient clearance inwardly from the wall of the cam chamber to permit a free flow of liquid upwardly through the passages 50 and 75

51 at all times. A pin 75 of a size and shape to permit hydraulic liquid to flow between it and the wall of the passage in which it is mounted, is inserted in each of the passages 50 and 51. 5 These pins are of a length normally to permit the lower ball checks 54 to seat, but to raise the balls off their seats when the pins 75 are raised by their respective cam lobes. The cam lobes 73 and 74 are arranged in partially overlapping and 10 partially angularly offset relation, as shown in Fig. 1. In this manner either one pin or the other or both may be raised by rotating the cam to bring the desired cam lobe or lobes into operating position. By turning the cam to move both cam lobes out of contact with both pins, it is apparent that both of the lower ball checks will be free to seat.

A lateral passage 77 shown in Figs. 4, 7, 8 and 9 connects the enlarged upper portions 53 of the vertical passages 50 and 51 to each other. This lateral connecting passage 77 in turn opens into the main fluid discharge passage 78 opening out of the forward end of the block 11. A fitting 79 may be threaded into the forward end of this passage to connect the apparatus to a mechanism (not shown) to be supplied with the hydraulic fluid.

The above-described passages and associated parts comprise essentially the fluid intake, compression, control and discharge of the high pressure, low volume, side of the hydraulic apparatus embodying the present invention.

Referring now to the passages associated with the low pressure, high volume cylinder 44 and its piston 43, a cylindrical valve chamber 80 is drilled upwardly from the bottom of the block 11, as shown in Figs. 4, 7 and 9. This valve chamber 80 has an enlarged threaded lower end portion 81. From the upper end of the valve chamber 80, a passage 82 of reduced diameter opens upward, and at the upper end of this reduced passage the passage is enlarged as at 83 to provide a valve seat for an inlet ball check valve 84.

A seat for a second, or outlet ball check valve 45 87 is formed between the upper end of the first enlarged passage 83 and a further enlarged passage 85. The upper end of the passage 85 is plugged as at 88.

A lateral passage 76 (see Figs. 7, 8 and 9) opens 50 into the first enlarged passage 83, between the upper and lower ball checks, and this lateral passage also opens into a vertical passage 86 which in turn opens into the main intake passage 47 from the reservoir 12.

A valve piston 89 is mounted slidably in the valve chamber 80, and a hydraulic sealing ring 90, which may be of resilient plastic material, is mounted in a groove in the piston 89. A stem 91 projects upwardly from the valve piston 89 and is surrounded by a biasing coil compression 60 spring 92 which is held in compression between the upper end of the valve chamber and the top of the valve piston 89. The upper portion 93 of the stem 91 is further reduced in diameter and is shaped to permit free flow of hydraulic liquid between it and the wall of the reduced passage 82 above the valve chamber 80 in which it is inserted. The length of this reduced stem portion 93 is such as to raise the lower or inlet ball check 84 off its seat upon a predetermined upward movement of the valve piston 89, and to permit the ball to reseat upon a predetermined return movement downward of the piston.

An axial opening 94 is drilled in the lower end 70 of the piston 89 to receive a stem 95 which ex-

tends upwardly from a combined sealing and valve pressure adjusting plug 97. A coil spring 99 surrounds the plug stem 95 and is held in compression between the bottom of the piston 89 and the top of the plug 97. The plug 97 is threaded into the enlarged lower end 81 of the valve chamber 80. The plug 97 may be adjusted axially by screwing it in or out as required to vary the force opposing the biasing action of the coil spring 92. A hydraulic sealing ring 98 is mounted in a groove in the plug 97.

From the first enlarged passage 83 between the ball checks 84 and 87 a passage 100 opens into the lower end of the large cylinder 44. A low pressure discharge passage 101 connects the upper enlarged passage 85 above the upper ball 87 to the transverse passage 71 which in turn opens into the main hydraulic discharge passage 78.

In order to connect the main discharge passage 78 with the valve chamber 80 below the valve piston 89, a vertical passage 102 extends downwardly from the main discharge passage 78 to a lateral passage 96. The passage 96 opens into a horizontal passage 103 which in turn opens into the valve chamber 80. See Figs. 4, 7, 8 and 9.

To permit the release of pressurized liquid from the main discharge passage 78, a hydraulic release needle valve 104 is provided. The valve 104 is threaded into a valve chamber 105 which opens into a co-axial passage 106 of smaller diameter than the valve chamber. A seat 107 for the needle valve 104 is provided at the offset between the valve chamber and the passage 106. The passage 106 opens into the vertical passage 102, which in turn opens into the main discharge passage 78. From the needle valve chamber 105 a horizontal passage 109 extends rearwardly and opens into the reservoir 12. Thus, upon opening the release valve 104 fluid is permitted to flow from the high pressure discharge passage 78 through the passages 108 and 106, through the valve chamber 105 and thence through the passage 109 back into the storage reservoir 12.

In describing the operation of the apparatus, let us assume that the discharge passage 78 is connected to a piece of hydraulic equipment such as a hydraulic press, not shown. In the use of such presses it is usually desirable to have the ram thereof move some distance before encountering the main work load to be imposed on it.

The loads which may be handled, of course, will vary with changes in the sizes of the three cylinders 37, 38 and 44, and the relative length of the handle 28 and that of the lever arms through which the pistons are operated. These values, of course, can be calculated readily and it is believed to be unnecessary to set them forth for any specific application.

Assuming that the apparatus is ready to be operated under a progressively increasing load, the adjusting plug 97 may be screwed in or out as desired to an adjusted position substantially as indicated in Figs. 4 and 7, so that the lower valve spring 99 partly compensates for the biasing action of the upper valve spring 92, but so that the reduced upper portion 93 of the stem 91 is not in contact with the lower ball check 84. The cam 62 may be turned manually to move both of the cam lobes 73 and 74 out of register with the ball operating pins 75 or into registry with either one, or both of said pins as required. The relief valve 104 is closed.

The free end of the handle 28 then is moved reciprocally up and down to move the lever 29,

and through it the three connected pistons 34, 35 and 43, reciprocally in their respective cylinders. Since the cylinder 38 is larger than the smallest cylinder 37 it will, of course, displace a larger quantity of hydraulic fluid than the latter. The third cylinder 44 not only is of larger diameter than either of the other two, but also it is pivoted at a greater distance from the fulcrum shaft 26, so that it will have a longer stroke than the other two cylinders. It therefore has a larger displacement than either of the other two cylinders.

Assuming for the purpose of illustration that the cam lobes 73 and 74 are out of registry with their pins 75, initially all of the lower ball checks 54 and 84 will be positioned on their seats. On an upward stroke of the operating handle 28 the free end of the lever 29 will rise, thereby raising all three pistons. This action, of course, reduces the pressure in the cylinders and permits the hydraulic liquid from the reservoir, under atmospheric pressure, to flow into all three cylinders through the intake passages previously described. On reaching the top of the handle stroke the atmospheric pressure from the reservoir is balanced by the stopping of the pistons and the lower ball checks 54 and 84 return to their seats by gravity.

On a downward stroke of the handle 28 the lever arm 29 forces the three pistons downwardly in their respective cylinders, thereby increasing the pressure on the liquid in each. This increase in pressure is transmitted to the passages between the upper and lower ball checks of each cylinder, and tends to force the lower ball checks in each instance onto their seats and to raise the upper ball checks from their seats. The upper ball checks will be raised from their seats as soon as the pressure below the ball checks increases beyond the pressure in the discharge passages above them.

Since the passages 102, 96 and 103 connect the discharge passage 78 to the valve chamber 80 between the piston 89 and the plug 97, the discharge pressure thus is transmitted to the lower surface of the valve piston 89, tending to force it upwardly against the biasing action of the upper coil spring 92. As soon as the discharge pressure which thus is transmitted to the lower face of the valve piston 89 increases sufficiently to raise the valve piston to a height which will lift the lower ball check 84 off its seat, the largest cylinder 44 is thereby made inoperative, since further operation of the piston merely causes a flow of liquid back and forth through the inlet passages past the open lower ball check 84.

As it is assumed, for the present illustration, that both the cam lobes 73 and 74 are out of registry with their pins 75, continued operation of the handle after the largest cylinder 44 has thus been made inoperative will be at a much greater mechanical advantage than before. The output then will be entirely by the two smaller cylinders 37 and 38, with their pistons operating through a shorter lever arm than the largest piston.

If thereafter the load increases to a point where it is beyond the capacity of both of the two smaller cylinders 37 and 38, either one or the other of these two cylinders can be made inoperative by turning the cam handle 67 to bring either of the cam lobes 73 or 74 into engagement with the pin 75 of the cylinder it is desired to make inoperative. This raises the lower ball check 54 of the selected cylinder and prevents further pumping action by that cylinder. The upper ball check 55 of the inoperative cylinder holds the

fluid in the pressurized, or delivery zone against escape.

If it should be desired to halt the pumping action at the moment the largest cylinder 44 cuts out, as for example to check the position of a die upon completion of a traverse and before applying additional power, the cam handle 68 may be turned to bring both cam lobes 73 and 74 into engagement with their respective pins 76 to raise both inlet ball checks 54 from their seats. When this is done, upon the pressure in the discharge passage rising sufficiently to move the valve piston 89 upwardly to lift the lower ball check 54 from its seat, all three cylinders will thereupon be inoperative. The pressure will be held at this point until pumping is continued with either the cylinder 37 or 38, or both, made operative by turning the cam handle 68 to move the cam lobe controlling the selected cylinder out of contact with the pin 75 controlling the ball check for that cylinder.

After a working stroke of the operated mechanism has been completed, the pressure in the delivery zone can be released by turning the needle valve 104 to open it. Upon opening the needle valve, the pressurized liquid is free to flow from the main discharge passage 78 back into the reservoir 12.

While I have illustrated and described a preferred form of my invention, it will be clear to those familiar with the art that modifications can be made without departing from the spirit of the invention. Therefore, it is not desired to limit the invention except as specifically defined in the appended claims.

I claim:

1. A hydraulic apparatus comprising, in combination, a high pressure cylinder, a low pressure cylinder, common outlet means connected to both cylinders, separate inlet means for each cylinder, a piston operatively mounted in each cylinder, a biased pressure operated valve operatively controlling the low pressure cylinder, and a pressure transmitting connection between the common outlet and the pressure operated biased valve to transmit pressure from the common outlet to the valve in a direction opposed to the bias of the valve to move the biased valve on the attainment of a predetermined pressure in the common outlet to inactivate the low pressure cylinder.

2. A hydraulic apparatus comprising, in combination, a high pressure cylinder, a low pressure cylinder, common outlet means connected to both cylinders, separate inlet means for each cylinder, a piston operatively mounted in each cylinder, a check valve operatively mounted between the common outlet and each cylinder, a check valve operatively mounted in the inlet to each cylinder, a biased pressure operated valve control member operatively controlling the inlet to the low pressure cylinder, and a pressure transmitting connection between the common outlet and the pressure operated biased valve to transmit pressure from the common outlet to the valve in a direction opposed to the bias of the valve to move the biased valve on the attainment of a predetermined pressure in the common outlet to inactivate the low pressure cylinder.

3. A hydraulic apparatus comprising, in combination, a high pressure cylinder, a low pressure cylinder, common outlet means connected to both cylinders, separate inlet means for each cylinder, a piston operatively mounted in each cylinder, a check valve operatively mounted between the

common outlet and each cylinder, a check valve operatively mounted in the inlet to each cylinder, a biased pressure operated valve control member comprising a cylindrical housing, a floating piston operatively mounted in the housing, spring biasing means mounted to act on one side of said piston, adjustable spring counterbalancing means mounted to operate on the other side of said piston, and a pressure transmitting connection between the common outlet and the pressure operated biased valve to transmit pressure from the common outlet to the valve in a direction opposed to the bias of the valve to move the biased valve on the attainment of a predetermined pressure in the common outlet to inactivate one of said cylinders.

4. A hydraulic apparatus comprising, in combination, a plurality of high pressure cylinders, a low pressure cylinder, common outlet means connected to both cylinders, separate inlet means for each cylinder, a piston operatively mounted in each cylinder, cam means selectively controlling the inlet to each high pressure cylinder, a biased pressure operated valve operatively controlling the inlet to the low pressure cylinder, and a pressure transmitting connection between the common outlet and the pressure operated biased valve to transmit pressure from the common outlet to the valve in a direction opposed to the bias of the valve to move the biased valve on the attainment of a predetermined pressure in the common outlet to inactivate one of said cylinders.

5. A hydraulic apparatus comprising, in combination, a cylinder block having a fulcrumed handle, a high pressure cylinder and a low pressure cylinder in said cylinder block, a piston operatively mounted in each cylinder, means operatively connecting the pistons to the fulcrumed handle, common outlet means connected to both cylinders, separate inlet means for each cylinder, a check valve associated with each cylinder normally to prevent return flow of liquid from the cylinder toward its inlet, a secondary check valve operatively mounted between each cylinder and a common outlet normally to prevent flow of liquid from the outlet toward the cylinder, a spring biased pressure actuated member associated with one of said inlet valves, and a pressure transmitting connection between the common outlet and the pressure operated biased member to transmit pressure from the common outlet to the biased member in a direction opposed to the bias of the biased member to move the biased member relatively to one of said inlet check valves on the attainment of a predetermined pressure in the common outlet to unseat said inlet check valve.

6. A hydraulic apparatus comprising, in combination, a cylinder block having a plurality of cylinders formed therein, an operating handle fulcrumed on the cylinder block, a piston operatively mounted in each cylinder, means operatively connecting the pistons to the handle, a liquid reservoir, a separate inlet passage from the reservoir into each cylinder, an inlet check valve between each cylinder and the reservoir, a common outlet for both cylinders, an outlet check valve between the common outlet and each cylinder, a biased valve control member normally out of restrictive relation with the inlet check valves, pressure operated means mounted to oppose the bias of the valve control member, and pressure transmitting means operatively connecting the common outlet and the pressure operated means, to operate the pressure operated means on a predetermined increase in outlet pressure, thereby to move the

biased valve control member into valve opening relation to one of the inlet check valves.

7. A hydraulic apparatus comprising, in combination, a cylinder block, an operating handle fulcrumed on the cylinder block, a plurality of cylinders in the cylinder block at different distances from the fulcrum, a piston operatively mounted in each cylinder, means connecting the pistons to the handle at a distance from the fulcrum substantially equal to the distances of the respective cylinders from the fulcrum, a liquid reservoir, a separate inlet passage from the reservoir into each cylinder, an inlet check valve between each cylinder and the reservoir, a common outlet for both cylinders, an outlet check valve between the common outlet and each cylinder, a biased valve control member normally out of restrictive relation with the inlet check valves, pressure operated means mounted to oppose the bias of the valve control member, and pressure transmitting means operatively connecting the common outlet and the pressure operated means, to operate the pressure operated means on a predetermined increase in outlet pressure, thereby to move the biased valve control member into valve opening relation to one of the inlet check valves.

8. A hydraulic apparatus comprising in combination a cylinder block, a shaft pivoted on the block, an operating handle secured to the shaft, a piston actuating lever secured to the shaft, a pair of pivot pins carried by the lever at different distances from the shaft, a pair of pistons operatively connected to the pivot pin which is closer to the shaft, a single larger piston operatively connected to the pivot pin which is farther from the shaft, a cylinder in the cylinder block operatively receiving each piston, a liquid reservoir, a separate inlet passage from the reservoir into each cylinder, an inlet check valve between each cylinder and the reservoir, a common outlet for both cylinders, an outlet check valve between the common outlet and each cylinder, a biased valve control member normally out of restrictive relation with the inlet check valves, pressure operated means mounted to oppose the bias of the valve control member, and pressure transmitting means operatively connecting the common outlet and the pressure operated means, to operate the pressure operated means on a predetermined increase in outlet pressure, thereby to move the biased valve control member into valve opening relation to one of the inlet check valves.

9. A hydraulic apparatus comprising, in combination, a cylinder block, a plurality of cylinders formed in the cylinder block, an operating handle fulcrumed on the cylinder block, a piston operatively mounted in each cylinder, means operatively connecting the pistons to the handle, a liquid reservoir, a separate inlet passage from the reservoir into each cylinder, an inlet check valve between each cylinder and the reservoir, a common outlet for both cylinders, an outlet check valve between the common outlet and each cylinder, a cylindrical valve chamber formed in the cylinder block, a floating piston mounted in the cylindrical valve chamber, a pin operatively connected to the piston and movable by the piston into unseating engagement with the inlet check valve of one of the cylinders, a spring mounted to exert a biasing force on the piston away from such unseating movement, a second spring mounted to exert a force on the piston opposed to that of the first spring, adjusting means mounted to adjust the relative forces of the two springs, and pressure transmitting means con-

nected to the common outlet and to the side of the piston opposed to the biasing spring to move the pin into unseating engagement with its check valve on a predetermined increase in pressure in the common outlet.

10. A hydraulic apparatus comprising, in combination, a cylinder block, a plurality of cylinders formed in the cylinder block, an operating handle fulcrumed on the cylinder block, a piston operatively mounted in each cylinder, means operatively connecting the pistons to the handle, a liquid reservoir, a separate inlet passage from the reservoir into each cylinder, an inlet check valve between each cylinder and the reservoir, a common outlet for both cylinders, an outlet check valve between the common outlet and each cylinder, a cylindrical valve chamber formed in the cylinder block, a floating piston mounted in the cylindrical valve chamber, a pin operatively connected to the piston and movable by the piston into unseating engagement with the inlet check valve of one of the cylinders, a spring mounted to exert a biasing force on the piston away from such unseating movement, a second spring mounted to exert a force on the piston opposed to that of the first spring, adjusting means mounted to adjust the relative forces of the two springs, pressure transmitting means connected to the common outlet and to the side of the piston opposed to the biasing spring to move the pin into unseating engagement with its check valve on a predetermined increase in pressure in the common outlet, a pressure release passage from the common outlet to the reservoir, and a pressure release valve mounted in the pressure release passage, said pressure release valve having a closed condition to prevent flow of liquid from the common outlet to the reservoir through the passage, and an open condition to release liquid from the common outlet through the passage to the reservoir.

11. In a multi-stage pressure generator, a plurality of cylinders, a fluid reservoir, valve controlled conduit means connecting the cylinders with the reservoir and with an outlet, a piston operatively mounted in each cylinder, lever means connecting the pistons to a common fulcrum, and pressure actuated release means operatively connected with one of said cylinders to make ineffective the motion of the piston in said one cylinder on the attainment of a predetermined outlet pressure.

12. In a multi-stage pressure generator, a plurality of cylinders, a fluid reservoir, valve controlled conduit means connecting the cylinders with the reservoir and with an outlet, a piston operatively mounted in each cylinder, lever means of different lengths connecting the pistons to a common fulcrum, and pressure actuated release means operatively connected with one of said cylinders to make ineffective the motion of the piston in said one cylinder on the attainment of a predetermined outlet pressure.

13. In a multi-stage pressure generator, a plurality of cylinders, a fluid reservoir, valve controlled conduit means connecting the cylinders with the reservoir and with an outlet, a piston mounted in each cylinder, lever means of different lengths connecting the pistons to a common fulcrum, and pressure actuated release means operatively connected to the cylinder having its piston operated by a longer of said lever arms to make ineffective the motion of the piston in said latter cylinder on the attainment of a predetermined outlet pressure.

11

14. In a multi-stage pressure generator, a plurality of cylinders, a fluid reservoir, valve controlled conduit means connecting the cylinders with the reservoir and with an outlet, a piston mounted in each cylinder, lever means connecting the pistons to a common fulcrum, to produce different displacements in different cylinders, and pressure actuated release means operatively connected to a larger displacement cylinder to make ineffective the motion of the piston in said latter cylinder on the attainment of a predetermined outlet pressure.

15. In a multi-stage pressure generator, a plurality of cylinders, a fluid reservoir, a common outlet from said cylinders, a piston mounted in each cylinder, conduits connecting said reservoir to said cylinders and other conduits connecting said cylinders to said outlet, inlet and outlet check valves associated with each said cylinder respectively controlling flow into and out of said cylinders through said conduits in response

5

to reciprocation of said pistons, means for reciprocating said pistons, pressure actuated means for moving the inlet check valve associated with one of said cylinders to open position, means rendering said pressure actuated means responsive to the fluid pressure at said outlet, and means inhibiting actuation of said pressure actuated means until a fluid pressure of predetermined value is attained at said outlet.

12
